Fig. 1

FIG. 1 is a top plan view of a casserole cover showing my new design.

FIG. 2 is a side elevational view.

FIG. 3 is an end elevational view.

The essential feature of the design resides in the particular ornamentation and its arrangement on the upper surface of the cover.

I claim:

The ornamental design for a casserole cover or the like, as shown and described.
